DOCTOR BLADE

Fred George, Lakewood, Ohio, assignor, by mesne assignments, to Interchemical Corporation, New York, N. Y., a corporation of Ohio

Application January 5, 1937, Serial No. 119,104

13 Claims. (Cl. 101—169)

This invention relates to improvements in doctor blades for gravure printing presses, that is to say blades for removing excess ink from intaglio printing plates or cylinders. In such printing elements the image is commonly produced on the plate photographically through a lined screen and then etched, forming depressions of uniform area separated from each other by minute lands, the depressions varying in depth and in the printing operation carrying more or less ink, as the high lights and shadows of the image demand.

In photogravure printing wherein an etched cylinder carrying the image is partially immersed in a bath of fluid ink, the excess ink remaining on the cylinder over that required to fill the depressions is removed, in the conventional procedure, by causing a metallic blade, called a doctor blade, to bear against the surface of the rotating cylinder, the doctor blade being set at an angle somewhere between 10° and 30° from the radial plane passing through the line of contact. In other words, the doctor blade is arranged at an angle somewhere between 60° and 80° from the tangent at the point of contact. The purpose of such a blade is to remove completely the ink from the outer surface of the cylinder and leave only that carried within the depressions. It will be seen therefore that the character of the printed image for a given quality of ink will remain substantially constant, and that any desired variations in the amount of color deposited must be accomplished by changes in the quality of the ink or by employing a different cylinder having a design engraved to a different depth. Metallic doctor blades or other blades of hard material are open to various objections, such as the need for accurate regrinding of the blade due to wear, gradual wearing off of the design on the cylinder by the abrasive action of the blade, and a tendency to scratch the surface of the cylinder.

According to the present invention, a doctor blade of relatively soft resilient material is provided, together with a method of mounting and adjusting the pressure of the blade against the cylinder, whereby abrasive action between the blade and the cylinder is reduced and variations in the character of the printing are obtainable by means of simple adjustments of the doctor blade.

One of the objects of the invention is to provide a doctor blade for gravure printing machines, the active portions of which shall produce no appreciable wear on the cylinder or

printing plate and cause no scratches or other injury to the printing surface.

Another object is the provision of a suitable mounting for soft flexible doctor blade material.

Still another object is the provision of a doctor blade of a character such that variations in the pressure exerted through the blade against the printing surface will cause variations in the amount of ink left upon the printing surface.

Other objects and features of novelty will appear as I proceed with the description of that embodiment of the invention which, for the purposes of the present application, I have illustrated in the accompanying drawings, in which

Fig. 1 is a side elevational view, largely diagrammatic, of a gravure printing press showing only essential elements thereof, and embodying the present invention.

Fig. 2 is a detail view showing a modification of the doctor blade.

Figs. 3, 4 and 5 are sectional views on a greatly magnified scale showing the effect of different adjustments of the doctor blade.

Referring to Fig. 1, 10 is the frame of a gravure printing press, of which 11 is the printing cylinder having an intaglio printing surface of the usual photogravure character. The cylinder 11 is carried by shaft 12 which may be driven by suitable power means 9. 13 is a rubber-covered cylinder adapted to press the web being printed against the printing cylinder, and 14 is a metallic back-up roller for maintaining constant pressure between the rubber roller 13 and the printing cylinder throughout their length. The shafts of rollers 13 and 14 are carried in bearing blocks slidably movable in a radial direction with respect to cylinder 11, suitable means such as screws 15 being provided for adjusting the pressure exerted by roller 14. The web W of paper extends half-way around roller 14, passes between that roller and roller 13, extends half-way around roller 13 and passes between that roller and the printing cylinder 11, after which it passes through any known and suitable mechanism for drying the printed image and rewinding the web. The cylinder 11 upon which the printing design is formed or mounted is partially immersed in the ink 16 carried in an ink pan 17.

The ink clinging to the surface of cylinder 11 is in excess of that required to fill the depressions of the design is removed by means of a doctor blade which is shown in Fig. 1 as consisting of three parts, a thin soft strip 18 of resilient material such as soft rubber, the end of the strip 18

being cut square, a thicker strip 18 also resilient and somewhat soft or yielding although less resilient and less soft than strip 18, and a hard backing strip 20 which is preferably metallic. 5 All three of these strips are clamped firmly together by means of bars 21 and 22 and bolts 23, the bars running the full length of the doctor blade. To the bar 22 are fastened brackets 24, one at each end, which are secured to a shaft 10 25 that is journaled in the side frames of the press. To each end of shaft 25 outside of the frame of the press there is attached an arm 26, and upon these arms weights 27 of selected size may be hung in order to exert forces of different strength producing varying pressures of the doctor blade against the surface of the printing cylinder 11.

As illustrated in the drawings my doctor blade is mounted nearly but not quite tangent to the 20 cylinder, which mounting is in sharp contradistinction to the mounting of the conventional hard blade which is positioned nearly at right angles to the tangent. This is an important feature of the invention. In practice I have found 25 that for average conditions the most desirable angle of the blade with reference to the tangent at the line of contact is 13° or thereabouts. This angle may be varied advantageously to some extent to suit different conditions, such as changes 30 in the speed of rotation of the printing cylinder, changes in the ink used, and changes in the pressure of the blade against the cylinder. In no case however should the angle exceed 30°.

I have found that soft rubber, either natural 35 or synthetic, is a suitable material for the strip 18, but it will be understood that other flexible soft materials having more or less similar characteristics of softness and resiliency may be substituted with good results. The two strips 18 and 19 of Fig. 2 may be joined together by cement or otherwise, or they may be joined together by vulcanization.

For certain purposes one thickness only of rubber or the like may be required. Such an 45 arrangement is shown in Fig. 2, in which the soft flexible portion 28 of the blade is backed up by a more or less stiff metallic strip 29 and mounted in the way previously described. A single strip of rubber may also be composed of 50 layers or zones of different resiliency and softness graded progressively from the backing to the engaging surface.

In Figs. 3, 4 and 5 I have illustrated on a magnified scale a small section of the etched 55 plate or cylinder with the soft doctor blade wiping off the ink, Fig. 3 showing the average or normal pressure adjustment for removing all ink from the surface or lands while leaving the depressions filled. The depressions are indicated at 30 and the lands at 31. It will be noted that the bottom and end surfaces of the strip 18 of the doctor blade are at right angles to each other, but that the pressure exerted through this 60 strip has deformed the engaging edge to some extent. In other words instead of a true line contact between the blade and the cylinder we have contact over a very narrow surface conforming to the curvature of the cylinder.

70 In Fig. 4 the pressure exerted is less than in Fig. 3, and the deformation of the active edge of the strip 18 is less. With this adjustment the depressions 30 are left filled as before, but in addition there is left upon the lands 31 a thin film of ink. When a print is taken from

a plate inked in this manner the whole image is darkened slightly over what it would be if printed from the same plate inked in the manner indicated in Fig. 3.

In Fig. 5 the pressure induced by the weights 5 21 or the like is increased above normal and to such an extent that the active edge of the blade strip 18 is forced into the depressions 30 and wipes some of the ink out of those depressions as well as removing all ink from the 10 outer printing surfaces. By thus removing a quantity of ink from all of the depressions throughout the extent of the printing surface the tone of the print taken from the surface 15 is of course lightened or weakened.

It will be apparent therefore that the operator of a press equipped with my novel doctor blade may, by merely varying the pressure exerted on the doctor blade, and without changing the speed of the press or the character of the 20 ink used, produce prints that vary in tone or depth over a considerable range. The ink carried up by the cylinder and held back by the doctor blade forms a wedge-shaped reservoir 32, as shown in Figs. 3, 4 and 5, which because of 25 the rotation of the cylinder is under a pressure tending to force it past the blade. This effect combined with the resiliency of the rubber blade permits accurate regulation by pressure changes of the amount of ink allowed to pass the blade, 30 as in Fig. 4. In so far as the condition illustrated in Fig. 4 is concerned, speeding up the cylinder has the same effect as decreasing the pressure on the blade.

Variations from the described structure may 35 be employed. Accordingly I desire it to be understood that the scope of the invention is to be regarded as defined exclusively by the appended claims rather than by the foregoing description or the accompanying illustration.

Having thus described my invention, I claim:

1. A doctor blade for a printing element of the intaglio surface type, said blade comprising a plurality of layers of resilient material, the foremost layer being of such softness as to require external support, said foremost layer being adapted in operative position to contact said printing surface, and substantially rigid supporting means adapted to prevent deflection of said layers.

2. A doctor blade for a printing element of the intaglio surface type, said blade comprising a resilient surface contacting portion of such softness as to require external support, and a plurality of layers of material of increasingly 55 greater stiffness for supporting said surface contacting portion in operative position.

3. A doctor blade for a printing element of the intaglio surface type, said blade comprising a plurality of strips of resilient material of different degrees of stiffness, said strips being arranged with the softest strip in contact with the printing surface to remove ink therefrom, and a backing strip of material harder than 65 the first mentioned strips.

4. In a gravure printing press, an intaglio printing cylinder having a screened, etched, surface, a cooperating impression cylinder, and a doctor blade operatively associated with said 70 printing cylinder and having a soft resilient ink removing edge.

5. In a gravure printing press, an intaglio printing cylinder having a screened, etched, surface, a cooperating impression cylinder, a doctor

blade operatively associated with said printing cylinder and having a soft resilient ink removing edge, and means for applying varying amounts of pressure to said doctor blade so as to produce different printed tone effects.

6. A gravure printing press, comprising an intaglio printing cylinder having a printing surface of the usual photogravure character; an impression cylinder cooperating with said printing cylinder; means for applying marking material to said printing cylinder; and a doctor blade having a soft resilient wiping edge operatively arranged substantially tangent to said printing cylinder.

11. A gravure printing press, comprising an intaglio printing cylinder having a printing surface of the usual photogravure character; an impression cylinder cooperating with said printing cylinder; means for applying marking material to said printing cylinder; and a doctor blade having a soft resilient wiping edge operatively arranged at an angle of less than 30° with respect to the tangent at the line of contact of said doctor blade with said printing cylinder.

7. A gravure printing press, comprising an intaglio printing cylinder having a printing surface of the usual photogravure character; an impression cylinder cooperating with said printing cylinder; means for applying marking material to said printing cylinder; and a doctor blade having a soft resilient wiping edge operatively arranged at an angle of less than 30° with respect to the tangent at the line of contact of said doctor blade with said printing cylinder.

8. A gravure printing press, comprising an intaglio printing cylinder having a printing surface of the usual photogravure character; an impression cylinder cooperating with said printing cylinder; means for applying marking material to said printing cylinder; and a doctor blade having a wiping edge of such softness as to be deformed in the region of said edge by the pressure of the blade against said printing cylinder.

9. A gravure printing press, comprising an intaglio printing cylinder having a printing surface of the usual photogravure character; an impression cylinder cooperating with said printing cylinder; means for applying marking material to said printing cylinder; a doctor blade having a wiping edge of such softness as to be deformed in the region of said edge by the pressure of the blade against said printing cylinder; and means for varying the pressure of said doctor blade against the cylinder in order to control the tone effect of the prints produced.

10. A gravure printing press comprising an intaglio printing cylinder having a printing surface of the usual photogravure character; an impression cylinder cooperating with said print-

ing cylinder; means for applying marking material to said printing cylinder; and a doctor blade comprising a strip of material having the softness and resiliency characteristics of soft rubber, a backing therefor, and means for exerting pressure through said backing to cause said strip to bear against the printing cylinder for removing marking material therefrom.

11. A gravure printing press comprising an intaglio printing cylinder having a printing surface of the usual photogravure character; an impression cylinder cooperating with said printing cylinder; means for applying marking material to said printing cylinder; and a doctor blade comprising a strip of material having the softness and resiliency characteristics of soft rubber, arranged to bear against the printing cylinder for removing marking material therefrom, the cylinder contacting portion of the strip being formed of two faces substantially at right angles to one another.

12. A gravure printing press comprising an intaglio printing cylinder having a printing surface of the usual photogravure character; an impression cylinder cooperating with said printing cylinder; means for applying marking material to said printing cylinder; and a doctor blade comprising a printing cylinder contacting portion having the softness and resiliency characteristics of soft rubber, means for supporting said portion throughout the length thereof, and means for exerting varying amounts of pressure against said supporting means in a direction toward said printing cylinder in order to control the tone effect of the prints produced.

13. A gravure printing press comprising an intaglio printing cylinder having a printing surface of the usual photogravure character; an impression cylinder cooperating with said printing cylinder; means for applying marking material to said printing cylinder; and a doctor blade comprising a strip of material having the softness and resiliency characteristics of soft rubber, a backing therefor, and means for exerting pressure through said backing to cause said strip to bear against the printing cylinder in such a manner that a thin film of marking material will be left upon the surface of said printing cylinder.

FRED GEORGE. 50
